APPARATUS FOR SUPPORTING CABLES FOR SCRAPERS AND LIKE DEVICES

Henry B. Hillyer, Eveleth, Minn.

Application March 22, 1933, Serial No. 662,154

8 Claims. (Cl. 254—130)

The invention relates to apparatus for improving the operation of scrapers and has particular application to means for deflecting the main haulage rope of the scraper around a corner to facilitate the slushing of ore in mines.

The invention contemplates the provision of apparatus for changing the direction of travel of the scraper and more specifically apparatus for attachment to a post or other support to enable the haulage cable of the scraper to pass around a corner whereby the scraper may have an uninterrupted travel, as, for example, from a raise in a mining drift to the working face of the slice which leads at right angles from the drift.

Accordingly, an object of the invention resides in the provision of a system of rollers arranged to deflect a haulage cable at right angles and which will also allow passage of lead and tail ropes spliced to the haulage cable and which join a scraper or other device to the main cable.

With these and various other objects in view, the invention may consist of certain novel features of construction and operation as will be more fully described and particularly pointed out in the specification, drawings and claims appended hereto.

In the drawings which illustrate an embodiment of the device and wherein like reference characters are used to designate like parts—

Figure 1 is a plan view of a portion of an ore mine showing the use of the invention for directing the scraper from the working face of the slice to the slusher hoist;

Figure 2 is a top plan view of the improved apparatus of the invention;

Figure 3 is a side view of the device showing the eye bolts for adjustably clamping the same to a supporting post;

Figure 4 is a front elevational view of the apparatus; and

Figure 5 is an enlarged elevational view of the drift and slice of Figure 1, illustrating actual operation of the invention.

In the standard top slicing method of mining a raise 10 leads from a horizontal mining drift, for providing a vertical passage through which the ore is removed from the drift. In mining the ore slices 12 are formed at right angles thereto, the slices continuing along the drift on both sides thereof until the entire sub-level has been mined. As a slice is often at some distance from a raise scrapers 13 are commonly employed for transporting the ore from the working face 14 of the slice to the raise, which involves travel of the scraper around the right angle corner formed by

the slice and the mining drift. In these slushing operations, as they are known, it is therefore necessary to provide apparatus for location at the junction of the slice with its mining drift, which will allow passage of the main haulage cable and also the lead and tail ropes connecting with the scraper.

Referring more particularly to Figures 2, 3 and 4 the improved apparatus of the invention is shown as comprising a supporting member 15 formed of a plurality of members, each having a right angled bend to provide securing flanges 16 and 17 and cooperating horizontal flanges 18 and 19. Flange 18 has a centrally cutout portion 20 providing side sections which are reinforced by the flanges 19. The right angle members are suitably secured together as by welding, the completed unit being fastened to a post or other supporting structure 21 by securing chains 22 having connection at their ends to the eye bolts 23 and 24. A bolt 23 passes through one of the flanges 17 and also through flange 16 to one side of the center thereof, while a bolt 24 having threaded connection with nut 25 on the end of the chain passes through the other flange 17 and through flange 16 to the other side of the center. This disposition of the securing chains locates the same in spaced relation on the supporting post 21, which therefore engage with the supporting member 15 at the upper and lower extremities of the member so that the same is securely held in place, being prevented from rotative or bodily shifting movements.

The horizontal flange 18 having the reinforcing flange 19 located along the sides thereof provides a support for the vertical rollers 26, rotatively mounted through anti-friction bearings 27 on the threaded studs 28 having threaded engagement in the corner portions of the flange 18, each stud also passing through and being threaded to a reinforcing flange 19. The upper end of each stud is recessed at 30 for receiving a tool or other suitable member by which the stud can be readily turned to adjust the vertical position of the rollers 26. Flange 16 has its central portion reinforced by plate 31 to provide a suitable support for the horizontal roller 32, rotatably mounted through anti-friction bearings 33 to the threaded stud 34 having threaded engagement with the plate and flange. Locating the horizontal roller centrally of flange 16 positions the same between the vertical rollers and it will be noted that the outer edge of the horizontal roller extends inwardly to intercept the vertical plane formed by the inner edge of the vertical rollers. Since the

latter are vertically adjustable through rotation of studs 28 they have a variety of positions with respect to the horizontal roller, their exact location being determined by the slack existing in the main haulage cable.

Secured to the sides of flange 18 by means of the depending lugs 35 are slab rollers 36. Each roller is angularly disposed with respect to the side edge of the flange 18, being adapted to engage the haulage cable and to limit the upward movement of said cable. The structure shown is preferred, although the rollers may be replaced by horizontal flanges on the upper end of the vertical rollers without affecting the efficiency of the apparatus. The main haulage cable 38 leads from the slusher hoist 40, located beyond the raise 10 to the pulley or sheave 41 located in the working face of the slice. Lead and tail cables 42 and 43 respectively, connect the scraper 13 to one section of the main cable, which section is deflected around the corner at the junction of the slice with the mining drift by the system of rollers described, the cable being supported vertically by the horizontal roller 32 and being held in position thereover by the spaced vertical rollers 26 located to the respective sides of the horizontal roller. The successful operation of the device depends upon the proper adjustment of the vertical rollers with respect to the horizontal roller and it will be seen that upon proper adjustment the lead and tail cables will readily pass over the rollers to thereby cause a change in the direction of travel of the scraper. To facilitate operation of the device the lead and tail cables are provided with weights 44 causing the cables to sag to minimize interference between the cables and the rollers.

It is to be understood that I do not wish to be limited by the exact embodiment of the device shown, which is merely by way of illustration and not limitation, as various and other forms of the device will be apparent to those skilled in the art without departing from the spirit of the invention or the scope of the claims.

I claim:

1. In a device of the character described, in combination, a supporting member having flanges disposed at an angle to each other, a plurality of rollers carried by said flanges and disposed in staggered relation, and means mounting certain of the rollers for adjustment in a direction axially of the roller.

2. In a device of the character described, in combination, a member having supporting flanges at an angle to each other, spaced studs threaded into one flange and carrying a roller on the depending end thereof respectively, a stud threaded into the other flange and carrying a roller on the projecting end thereof, said last mentioned roller being disposed between and in substantially the same horizontal plane as said spaced rollers.

3. In a device of the character described, in combination, a member having supporting flanges at an angle to each other, spaced studs threaded into one flange and carrying a roller on the depending end thereof respectively, a stud threaded into the other flange and carrying a roller on the projecting end thereof, said last mentioned roller

being disposed between said spaced rollers, and adjustable fastening means carried by the member for securing the same to a support.

4. In a device of the character described, in combination, a member having supporting flanges disposed at right angles to each other, one flange being horizontal and having spaced studs threaded into said flange and carrying rollers on the depending ends thereof, a stud threaded into the other flange and carrying a roller on the projecting end thereof, said spaced studs providing vertical axes for the rollers and said second mentioned stud providing a horizontal axis, and slab rollers located to the respective sides of said horizontal flange.

5. In a device for deflecting a haulage cable, comprising in combination, a supporting member disposed substantially vertically and having a horizontal flange projecting therefrom, a pair of spaced rollers carried on the depending ends of studs secured to said horizontal flange, a roller carried on the projecting end of a stud secured to the support and being located intermediate the spaced rollers whereby said haulage cable is supported in two directions by said rollers, and lead and tail ropes spliced to said cable have passage with respect to said device.

6. In a device for deflecting a haulage cable, comprising in combination, a member disposed substantially vertically and having a horizontal flange projecting therefrom, studs threaded to said horizontal flange and supporting rollers on their depending ends, whereby said rollers can be adjusted vertically with respect to the flange, a stud threaded to said support and mounting a roller on the projecting end thereof, said last mentioned stud being located intermediate the spaced studs and in a horizontal plane where the roller mounted thereon will cooperate with said depending rollers, whereby a haulage cable is supported by said rollers against movement in two directions and may be readily attached or removed from said device.

7. In a device for deflecting a haulage cable, comprising in combination, a member providing supporting flanges disposed at an angle to each other, studs secured at one of their ends to said flanges, and having an unsupported projecting end, rollers mounted on the projecting ends of the studs and having rotation on axes at an angle to each other whereby the haulage cable is supported in two directions by said rollers, and whereby lead and tail ropes spliced to said cable have passage with respect to the rollers.

8. In a device for deflecting a haulage cable at right angles, comprising in combination, a member having supporting flanges disposed at right angles to each other, one flange being horizontal and supporting spaced studs, rollers rotatably mounted on the depending ends of said studs, a stud projecting horizontally from said other flange and rotatably mounting a roller on the end thereof, whereby said rollers are disposed on axes at right angles to each other to support a haulage cable against downward movement and against outward movement in a direction away from said support.

HENRY B. HILLYER.
